UNITED STATES PATENT OFFICE.

LOUIS JENSEN AND CHARLES WINTER, OF CHICAGO, ILLINOIS, ASSIGNEES TO UNITED AUTOGRAPHIC REGISTER COMPANY, OF CHICAGO, ILLINOIS, A CORPORATION OF ILLINOIS.

AUTOGRAPHIC REGISTER.

Application filed January 25, 1924. Serial No. 688,493.

This invention relates to autographic registers and has particular reference to the mechanism which is employed to feed a summary or record strip a predetermined distance. The record strip in the present structure is not discharged from the register but is collected within the forward portion of the housing so that at the close of a business day, or whenever desired, a used portion of the record strip may be torn off and removed for the purpose of ascertaining the total sales up to that time. This mechanism is constructed and arranged so that the summary ticket may be fed and a portion may be removed without disturbing the other tickets or paper strips in the register. Suitable mechanism for initially starting the feed of the paper strips is cooperatively assembled with the record strip feeding mechanism. The operation of these two feeding mechanisms is so timed that the record strip is fed the desired distance prior to the starting of the feed of the other strips, and when this record feeding takes place the starter mechanism is set so that the operator may immediately begin the discharge of the other strips.

Among the numerous advantages of the present invention is the provision of means whereby the record strip will be fed always a predetermined distance, and also, in this connection, means have been provided so that any desired length of feed of said record strip with certain limits may be had by a simple adjustment which will limit the movement of the operating lever. A further object is to provide means whereby the feeding rollers for the record strip may be separated at the same time with the separation of the feeding rollers for moving the other strips through the register so that the mechanism may be simultaneously released for the purpose of adjusting the strips or for inserting of new strips whenever it is desired to replace the rolls of paper.

Further objects will, of course, be apparent to others skilled in this art, and said objects are accomplished in substantially the following manner, reference being had to the accompanying drawings that form a portion of this specification.

In the drawings:

Figure 1 is a vertical side view of the discharge end of an autographic register show-

ing a portion of the operating parts of the present invention thereon. 55

Fig. 2 is an elevation of the front or discharge end of the register, also showing the invention installed thereon.

Fig. 3 is a fragmentary side elevation of 60 the structure illustrated in Figure 1 showing the parts in another position.

Fig. 4 is a detail view, partly in section, of the latching means for maintaining the friction throw-out structure in position. 65

Fig. 5 is a vertical section of a fragmentary portion of a register, the view being taken on line 5—5 of Figure 2.

Fig. 6 is a view similar to Figure 5, showing the relative positions assumed by the 70 parts when the friction rollers have been separated or released.

Fig. 7 is a horizontal sectional view showing certain essential details of the starter mechanism. 75

Figure 8 is a transverse section of the structure illustrated in Figure 4.

The record strip, as is usually understood by this term, is a paper strip that is fed through the register from a roll and is disposed at the bottom of a plurality of strips that are moved over the platen. It is not customary, however, for the record strip to receive all of the notations or itemized list of the purchases, but only to receive the total amount of each sales ticket. Suitable provision is made by dividing the cover of the register in order that the sales-persons will always enter the total amounts of the respective sales tickets in the desired location so that it may be received by all of the strips including the record strip. It is therefore obvious that the record strip need not be fed the same distance the tickets are moved but only a distance sufficient to receive the total amount from the next or succeeding set of tickets. In the present instance, the summary strip or record strip accumulates in the forward portion of the register where it is within convenient reach and may be withdrawn by tearing the same, as will hereinafter appear. 90

The register, as seen in the drawings, comprises a suitable housing consisting of a rectangular base A, side walls B, a platen C connecting the upper edges of the walls, and said walls are provided with suitable means for mounting a plurality of rolls of 100

paper strips. The strips extend from said rolls over the rear edge of the platen and across the upper face thereof to the forward or discharge end where they are received between the friction elements of the ticket feeding mechanism, and said strips are maintained in desired position on the platen by a fenestrated cover plate D. This feeding mechanism, just referred to, comprises the feed roller 10, the spindles 11 at the ends thereof being extended through vertical slots 12 in the hollow posts 13 arising from the sides or top of the register and are yieldingly urged downwardly by expansion springs 14 positioned in said posts and compressed between said spindles, and the threaded plugs 15 that are screwed down into the upper open end of each post. Adjacent one end of roller 10 the same is provided with a pinion 16 that is in mesh with a pinion 17 upon the rotatable shaft 18, which latter extends beyond its bearings where it is provided with an operating crank or handle 19 so that when said handle 19 is rotated in the proper direction the roller 10 and shaft 18 revolve in unison. The shaft 18 is hollow and has therein a solid shaft 20 that is adapted to be moved longitudinally within said first shaft, and at its outer end portion the shaft 18 is provided with alining slots 21 through which a pin 22 extends that passes through a threaded sleeve 23 upon the outer shaft 18 and also through the inner shaft 20. Intermediate its ends the hollow shaft has an elongated slot 24 through which a pin 25 extends to secure a cone-shaped clutch element 26 of the starter upon said shaft, and said pin also extends through the inner shaft 20. Thus, it will be seen the cone element 26 of the clutch or starter, the inner shaft 20, and the threaded sleeve 23 are connected together and will rotate with the hollow shaft 18 but may be moved longitudinally with respect to the same. Feeding disks 27, preferably four, arranged in pairs, and the disks of each pair slightly spaced apart, as seen in Figure 2, are adapted to coat with the feed roller 10 to feed the paper strips and said elements have their peripheries serrated or milled so as to increase the friction therebetween. Surrounding shaft 18 between the clutch element 26 and the adjacent disk 27 is a coiled expansion spring 28 that urges the said clutch element 26 towards and into engagement with a coacting clutch member or annulus 29 that has a conical bore corresponding with the contour of the companion clutch element 26 so as to center the same upon the shaft 18 and move it against the collar 30 that is fixed on said shaft 18. The bore of the loose clutch element or annulus 29 is greater than the diameter of shaft 18 so that when its companion member is disengaged therefrom the member 29 will hang

loose upon the shaft, but when the clutch members have become engaged, as seen in Figure 2, the member 29 will be in frictional engagement with the roller 10 so as to initially feed the paper strips. 70

The paper strips are provided with spaced post-holes that are disposed at either the top or bottom edges of the tickets printed thereon, and when said post-holes come into registry with the feeding disks 27 75 the latter will engage the roller 10 through said holes and further movement of the tickets will be stopped. It is necessary, therefore, to initially feed the strips so as to move the paper a distance sufficient to have 80 the disks disengaged and be moved out of registry with the post-holes, and this is done through the medium of the clutch or starter mechanism just heretofore described. 85

Pivottally mounted upon a stud 31 projecting from the outside of the adjacent wall, is a rocking arm 32 that is disposed transverse to the axis of the extended end of the shaft 18 and is in a position to engage the threads of the sleeve 23. The portion of the rocker 90 arm 32 that engages the threads is slightly concaved and tapered as at 33 so as to conveniently engage the threads, and when the shaft 18 rotates in the proper direction said arm will cause the sleeve to move outwardly 95 until said arm has disengaged the threads at their inner ends, in which position it maintains said sleeve at the outer end of the shaft 18. This will consequently move the inner shaft 20 longitudinally and cause the 100 clutch members to disengage so as to leave the annulus 20 loose upon the shaft and disengaged from the roller 10. This takes place after the paper has moved a distance sufficient to have disks 27 again engage the 105 paper slightly beyond the post-holes. 110

Extending downwardly from the platen and inclined towards the front end of the register is a guide plate 34 over which the summary or record strip passes so that the same is directed to its separate feed mechanism, and extending upwardly from the base A is a curved wall 35 that provides a guard and prevents the record strip, which accumulates in the forward part of the register, being moved back into the other portion thereof and possibly interfering with the paper rolls or strips. Mounted at opposite ends in the side walls of the register is a rock shaft 36 that has secured to it a substantially U-shaped frame, the ends of the parallel arms of which are secured to the rock shaft so as to be moved therewith whenever the same is rocked. This U-shaped frame comprises spaced parallel arms 37 that extend forwardly and downwardly from the rock shaft adjacent the register walls, and at their lower ends, which are farthest from the rock shaft, said arms are connected by a cross piece 38 that is beveled at its lower edge to 125 130

provide a cutting blade against which the record strip may be torn. Extending transversely across this frame and having its ends journalled in the opposite arms 37 is an idle roller 39 that bears against a record strip feed roller 40 which is mounted upon a rotatable shaft 41 having its ends extended through the side walls of the register and are journalled therein. This shaft is actuated by the mechanism for feeding the summary strip which is interposed between said feed roller and the idle roller 39. The rocking frame is kept normally urged toward the feed roller 40 with the idle roller 39 in contact therewith by means of a coiled contraction spring 42 that is secured at one end to the register wall at a distance below the end of the frame and at the opposite end said spring is connected to the rocking frame.

In order to release the pressure of the roller 39 against the feed roller 40 and also to simultaneously separate roller 10 from the feeding disks 27 there is provided a suitable cam and its operating mechanism. This consists of a rock shaft 43 that is journalled in the side walls of the register and extends across the same below the feeding mechanism. Adjacent the register walls bell crank levers 44 are secured thereto, which levers are of irregular or angular shape and are fulcrummed adjacent their upper ends, as seen in Figures 5 and 6 of the drawings. The portion of the levers 44 which extend above the rock shaft 43 have segmental shaped or cam edges 45 that are eccentric to the axis of the rock shaft and are below and adjacent the spindles of feed roller 10 so that when the opposite ends of the levers 44 are raised said cam edges will engage the under segment of the spindles 11 and raise the same against the tension of the springs 14 until the roller is separated from the feed disks 27. The opposite ends of the levers 44 which are hook-shaped are connected by a horizontal rod 46, and carried adjacent one end of the latter is a latch device for supporting the structure when in elevated position. This latch consists of a block 47 that slides longitudinally on the rod 46 against an expansion spring 48 and carries the latch pin 49 that extends through the adjacent portion of the lever arm 44 so that when the structure has been raised to the position shown in Figure 6, the pin will be projected across the top of the adjacent side wall B of the register and maintain the structure in the elevated position until the latch has been released to permit the spring 42 to draw the structure back again. The U-shaped frame carrying the idle roller 39 has an arm 50 extending upwardly obliquely from one of the side pieces 37 and has therein an elongated slot 51 that is entered by a pin or bolt 52 projecting from the adjacent lever

arm 44. When the lever arm 44 is raised to the position shown in Figure 6, the pin or bolt 52 rides in the slot and raises the rocking frame so that the friction roller 39 is disengaged from the feed roller 40 and the summary strip is free to be moved independent of its feeding mechanism. Thus the pressure of the feeding rollers against all of the paper strips is released and they may be adjusted separately or all at the same time, according to the service required.

Upon the outer end of the rotatable shaft 41 is secured a pinion 53 that is in mesh with an idle gear 54 loosely mounted upon a headed stud 55 projecting from the adjacent wall of the register. Integral with or secured to the hub of this idle gear 54 is a ratchet disk 56, and loosely mounted upon the headed stub, so as to freely oscillate, is a rotary reciprocable plate 57 that carries a pawl 58 pivotally thereon so that it will engage the teeth of the ratchet 56. Fulcrummed at its lower end upon a pin 59 is a vertically disposed elongated operating lever 60 that extends upwardly to a convenient point at the forward end of the register and clear of the crank or handle 19. Intermediate its end this lever is connected by a link 61 with the adjacent portion of the oscillatory plate 57 so that upon each depression or movement of the operating lever upon its fulcrum, said plate will oscillate, causing the pawl to engage or disengage the ratchet and thereby intermittently rotate the gear and pinion together with the record strip feeding roller 40 connected therewith. The lever 60 is provided with a lateral extension 62 arranged at substantially right angles at its lower end, the outer end of the extension being connected to a contraction spring 63 that has its upper end connected to a pin 64 upon the side wall of the register so that the lever arm will be automatically returned to its normal position, as soon as its forward movement has been completed and the lever released by the operator. The return movement of the lever arm is limited and may be adjusted by means of an elongated screw threaded element 65 that is inserted through the threaded bore of a block 66 secured to the register side wall, and which, after being adjusted to the desired position, may be locked in place by the set screw 67. By adjusting the length of the portion of this threaded element which projects towards the lever arm 60, the same will act as a stop for the return movement of said lever 60. Thus, any desired amount of rotation of feed roller 40, and consequently a predetermined length of record strip, may be fed through the register feed at each reciprocation of the lever arm 60, and whenever it is desired to change the length of the record strip to be discharged, the element 65 may be reset to the desired location.

- The outer end of the rocking arm 32 is connected to an elongated vertically disposed link 68, the lower end of said link being provided with an elongated slot 69 to receive the lateral pin 70 projecting towards the register wall from the end of the lateral extension 62 of the operating lever. When the lever 60 is moved forwardly or away from the operator to feed the record strip, the pin 70 will move to the lower end of the slot 69 of the link and further movement will draw this link downwardly, thus moving the rocker arm 32 upon its pivot so as to raise the portion 33 thereof above and clear of the threads of the sleeve 23. The sleeve 23 is then free, together with the inner solid shaft 20, and the cone-shaped clutch element 26, to move longitudinally with respect to the hollow shaft 18, being urged by the expansion of spring 28. This will set the starter mechanism to initially feed the paper strips in the manner hereinbefore described, but after the record strip has been fed the desired or predetermined distance. Thus, it will be seen the record strip may be fed a predetermined distance each time the register is set to feed another set of tickets through the same, and the length of the feed of said record strip may be readily adjusted to the desired length. Also, it will be noted that simultaneously with the releasing of the record strip for the purpose of inserting new rolls or for the purpose of adjusting the strips, the feed mechanism for discharging the other paper strips from the register will also be released, all of which latter is accomplished by the upward movement of the rod 46.
- What is claimed as new is:—
1. In an autographic register a platen, means for feeding a paper strip across said platen and discharging the same therefrom, said means including control devices in combination with rollers for feeding a supplementary strip, a pawl and ratchet mechanism for actuating said rollers, which mechanism is operated in coaction with said control devices, and adjustable means for limiting the movement of said mechanism whereby a predetermined portion of the supplementary strip is fed during each operation of said rollers.
  2. In an autographic register a platen, means for feeding a paper strip across said platen and discharging the same therefrom, said means including control devices in combination with rollers for feeding a supplementary strip, a pawl and ratchet mechanism for actuating said rollers, a lever operatively connected to said mechanism and operated in coaction with said control devices, and adjustable means interposed in

the path of movement of said lever for limiting the same, whereby a predetermined portion of the supplementary strip is fed during each operation of said rollers.

3. In an autographic register a platen, means for feeding a paper strip across said platen and discharging the same therefrom, said means including control devices in combination with rollers for feeding a supplementary strip, a pawl and ratchet mechanism for actuating said rollers, a lever operatively connected to said mechanism and operated in coaction with said control devices, a member projecting laterally from the wall of the register and having a threaded aperture, and a rod screwed into said aperture and interposed in the path of movement of said lever to limit the same, whereby a predetermined portion of the supplementary strip is fed during each operation of said lever.

4. In an autographic register a platen, means for feeding a paper strip across said platen and discharging the same, a starter mechanism for initially feeding the strip, rollers for feeding a supplementary strip, a pawl and ratchet mechanism for actuating said rollers, an actuating lever operatively connected with said mechanism, adjustable means interposed in the path of movement of said lever for limiting the same, and a rocking lever for releasing said starter mechanism and actuated by said first-mentioned lever, whereby when said starter mechanism is released a predetermined portion of the supplementary strip is fed by said rollers.

5. A device of the kind described comprising a platen, paper feed rollers associated therewith, devices for controlling said rollers, separate rollers for feeding a supplementary strip on said platen, and mechanism operatively connected with said control devices for intermittently actuating said separate rollers, a portion of said mechanism being adjustable whereby to provide a predetermined feed of the supplementary strip.

6. A device of the kind described comprising a platen, paper feed rollers associated therewith, devices for controlling said rollers, separate rollers for feeding a supplementary strip on said platen, mechanism operatively connected with said control devices for intermittently actuating said separate rollers, and an adjustable stop engaged by a part of said mechanism whereby to provide a predetermined feed of the supplementary strip.

Signed at Chicago, county of Cook and State of Illinois, this 15th day of January, 1924.
